UNITED STATES PATENT OFFICE.

LEMUEL PATTERSON, OF OLEAN, NEW YORK.

WALL-PLUG.

No. 831,092.

Specification of Letters Patent.

Patented Sept. 18, 1906.

Application filed May 3, 1906. Serial No. 315,035.

To all whom it may concern:

Be it known that I, LEMUEL PATTERSON, a citizen of the United States, residing at Olean, in the county of Cattaraugus and State of New York, have invented new and useful Improvements in Wall-Plugs, of which the following is a specification.

This invention relates to wall-plugs; and the primary object of the same is to provide an inexpensive device of this class for use in brick, stone, or concrete-block buildings to serve as means for holding strips to receive lathing, or for other purposes, such as to secure and finish door and window casings, base-moldings, trimmings, &c.

The invention consists in the construction and arrangement of the several parts, which will be more fully hereinafter set forth.

In the drawings, Figure 1 is a perspective view of a portion of a wall, showing the improved plug disposed therein. Fig. 2 is a detail perspective view of the improved plug.

The plug 1 is formed with a wedge-shaped body having the reduced end thereof longitudinally cut or kerfed, as at 2, to receive nails. The maximum thickness of the plug is approximately the same as the distance between courses of bricks, blocks, or stones ordinarily occupied by mortar, cement, or other analogous material, and in building a wall the plugs are inserted at intervals between the courses of bricks, blocks, or stones, and at the reduced extremity of the plug sufficient mortar or cement is applied to make up or compensate for the difference in vertical extent of the two extremities of the plug and to insure a level position of the bricks or blocks. The cut, kerf, or slot 2 in one extremity of the plug is exposed between the courses of bricks or blocks, and when the plug is arranged at a corner the said cut or kerf extremity also has a side exposure, as shown by Fig. 1 of the drawings.

It will be understood that the improved plug will be formed from wood or analogous material, into which nails can be driven, but it is preferred that some cheap material be used adapted for the purpose and the plugs manufactured in bulk and shipped in boxes or barrels or otherwise prepared and transmitted as may be desired. In all applications of the plug the thickened extremity or

the end having the maximum vertical extent will be disposed in the inner part of the wall and the reduced extremity projected outwardly or terminated flush with the wall-face except when used at a corner of the wall, and under the latter conditions, as heretofore specified, the one side edge of the plug will also be exposed.

It will be seen that strips of every description may be readily attached to the plug by driving nails therethrough, which are caused to enter the slot 2 and operate to expand the latter and tighten the wedge between the courses of bricks or blocks, and thus set up a material resistance to the loosening of the wedge, as will be readily appreciated. It will also be understood that the proportions and dimensions of the plug may be varied at will, and in view of the simplicity of the construction of the same it can be manufactured at a small cost.

What I claim is—

1. As an improved article of manufacture, a wedge-shaped wall-plug having its reduced extremity longitudinally cut to provide separating members, the said members being normally in contact with each other throughout the full length of the cut and of a yielding nature.

2. As an improved article of manufacture, a wedge-shaped wall-plug having its reduced extremity longitudinally cut to produce expansible members, said members being normally in contact and expanded by the introduction therebetween of a fastening device.

3. The combination with a wall, of a wedge-shaped plug inserted between the courses of the members of the wall with its largest extremity innermost, the said plug having its outer reduced extremity longitudinally cut to provide expansible members, said members being normally in contact throughout the length of the cut and separated by the introduction therebetween of a fastening device.

In testimony whereof I affix my signature in presence of two witnesses.

LEMUEL PATTERSON.
